Primary Examiner — Mark A Goodwin*(74) Attorney, Agent, or Firm* — Tara M. Hartman**CLAIM**

The ornamental design for an appliance knob with bezel, as shown and described.

DESCRIPTION

Cross-reference is made to co-pending U.S. Design Patent application Ser. No. 29/359,104 entitled "Appliance Knob," which was filed on Apr. 6, 2010.

FIG. 1 is a front perspective view of an appliance knob with bezel showing my new design;

FIG. 2 is a front elevational view thereof;

FIG. 3 is a top plan view thereof;

FIG. 4 is a bottom plan view thereof;

FIG. 5 is a first side elevational view thereof; and,

FIG. 6 is a second side elevational view thereof.

The rear elevational views are not shown and form no part of the claimed design. The portion shown in broken lines is for illustrative purposes only and forms no part of the claimed design.
